RUBBER FINGER STALL TOOTHBRUSH

Roderick G. Stevens, Chicago, Ill.

Application December 8, 1934, Serial No. 756,561

6 Claims. (Cl. 15—188)

This invention relates to a rubber finger stall tooth brush of the type disclosed and claimed in Patent No. 1,965,009, issued July 3, 1934.

An important object of the present invention is to provide a finger stall tooth brush of the aforesaid type which is provided with enclosing side walls or a cap inclined with respect to the base so as to permit the device to be easily and quickly applied to the finger.

Another object of the invention is the provision of a finger receiving opening having its edges inclined forwardly and upwardly from the base to permit the finger to be easily and readily inserted in the opening.

Another object is to provide a "pull-on" tab which is made of the same material as the finger encasing cap, but slightly thicker, tapering in thickness from the open end toward the closed end and projecting a predetermined distance beyond the upper edge of the inclined enclosing wall of the device.

A further object of the invention is to provide a one-piece or rubber finger stall tooth brush made of soft flexible gum rubber which is provided with a reinforcing end about the outer edge of the material surrounding the opening, which is constructed and arranged to have the appearance of a conventional tooth brush, which is provided with means for permitting quick and ready application of the device to a finger, and which is durable in construction and not likely to tear or disintegrate during ordinary use, which can be readily and easily cleansed and maintained sanitary, and which may have the mold seam of the device at the center of the upper longitudinal rib or beading whereby the body of the stall strengthens the side walls of the stall and makes the device more durable.

Numerous other objects and advantages will be apparent throughout the progress of the following specification.

The accompanying drawing illustrates a selected embodiment of the invention and the views therein are as follows:

Fig. 1 is a detail perspective view of the improved gum rubber finger stall tooth brush.

Fig. 2 is a top plan view thereof.

Fig. 3 is a longitudinal sectional view thereof.

Fig. 4 is a transverse sectional view on the line 4—4 of Fig. 3.

Fig. 5 is a longitudinal sectional view through a modified form of finger stall tooth brush.

Fig. 6 is a detail end elevation of both forms.

The finger stall or cot 8 herein shown is provided with a body portion 7 made of relatively

thin yieldable stretchable material such as pure gum rubber and a supporting base portion 8 which may be made of the same material but which is relatively thick and not as freely stretchable as the thinner body portion. The forward end of the device may be substantially vertical as indicated at 9 to give the device the appearance of a conventional tooth brush. Spaced ribs 10 and 11 encircle the device to render it more durable as well as to give it a more pleasing appearance and accentuate the appearance of a tooth brush. The body portion 7, the base 8 and the plurality of upstanding teeth 12 are all integral, being molded in one piece from pure gum rubber. The base 8 is made concave as indicated at 13 to 15 permit one's finger to be easily inserted within the enclosed finger receiving opening. The material surrounding the opening 14 inclines upwardly and forwardly from the base as indicated at 15 and is strengthened by a rubber rib 16. The rubber rib or beading 16 extends around the opening of the stall and provides a constriction or contraction of the opening so that when the finger is inserted in the stall, the device is held more securely on the finger because the rib at the edge 25 of the opening is made relatively more tightly on the finger than are the side walls of the stall. This beading has a similar contraction or tension to a draw-string around the end of the opening despite the fact that the area of the opening is 30 larger due to the slanting thereof. A pull-on reinforced tab 17 extends from the forward end 18 of the device and increases in thickness toward its rear open end 19 projecting a predetermined distance beyond the upper inclined side walls 15 35 as indicated at 20. The pull-on tab and reinforcement permits of easier insertion of the finger. The pull-on tab can be given a relatively hard pull without tearing the same because of its reinforced thickness and because of the beading extending around the end. The slanting of the opening permits easy access to the finger end of the stall and makes it possible to use the end 21 of the base as a pull-on for the stall also. The slanting opening also makes possible freer use of 45 the finger in manipulation of the device upon the gums and teeth. The combination of the pull-on tab and the slanting opening makes it easy to fit the stall over the end of the finger quickly and easily without injuring the device in any way. 50 The beadings 16 and 11 running lengthwise of the brush give the device the finished mechanical appearance of a standard tooth brush. These beadings also emphasize the tapering effect of the brush, giving it a delicate appearance for 55

insertion into the oral cavity when applied to a finger.

The rubber papillæ 12 are spaced apart in rows, and transversely the bristles assume a somewhat arcuate arrangement to perform better the gum massaging operation for which the device is primarily intended.

If desirable, the base 8 may be extended a predetermined distance beyond the inside edge 22 as indicated at 23, Fig. 5, to provide a device with a more tapered end and provide a longer base. Such a construction, with a more distinct taper, enables the user to reach the back area of the gums more readily. This construction is also convenient for massaging the gums far back into the mouth.

The invention provides a strong, durable, easily applied finger stall tooth brush having soft flexible teeth or papillæ for massaging the gums.

20 The slanting opening at one end of the device permits a finger to be readily slipped into the opening, also permits the pull-on tab to extend beyond an edge of the upper part of the opening to assist in applying the device to a finger. The 25 pull-on tab is thicker progressively from the closed end toward the open end and has a bead thereon whereby it is practically impossible to tear the device during ordinary usage when applying it on a finger. The finger stall tooth brush in reality provides a tooth gum brush designed primarily for massaging the gums to stimulate circulation and harden the muscular fibres of the gum structure. The various elements constituting the device are constructed and arranged 30 so that the gum massaging operation can be most conveniently performed. Also, the device is so constructed as to give it a neat appearance so that practically and psychologically it will be easy to insert in the oral cavity and use upon the 35 entire gum surface. Furthermore, it is preferable that the device be made of a material assuring the utmost sanitation, being preferably made from pure gum rubber. The device is small, compact, can be readily applied and removed from a finger, takes up very little room and can be thoroughly and easily cleansed.

Changes may be made in the form, construction, and arrangement of the parts without departing from the spirit of the invention or sacrificing any of its advantages, and the right is hereby reserved to make all such changes as fairly fall within the scope of the following claims.

The invention is hereby claimed as follows:

- 55 1. A one-piece finger stall tooth brush made of flexible rubber-like material and having a base, teeth projecting from the base, a closed end and having a finger receiving opening, the material surrounding the opening forming a rib and 60 being inclined upwardly and forwardly from the rear portion of the base to permit easy insertion of a finger into the opening.
- 65 2. A one-piece finger stall tooth brush made of flexible rubber-like material and having a base, teeth projecting from the base, a closed end and having a finger receiving opening, the material surrounding the opening forming a rib and being inclined upwardly and forwardly from the base to permit easy insertion of a finger into the

opening, and a pull-on tab of flexible material extending substantially the full length of the brush and extending a predetermined distance beyond the inclined edges surrounding the opening.

3. A one-piece finger stall tooth brush made of flexible rubber-like material and having a base, teeth projecting from the base, a closed end and having a finger receiving opening, the material surrounding the opening forming a rib 10 and being inclined upwardly and forwardly from the base to permit easy insertion of a finger into the opening, a pull-on tab of flexible material extending substantially the full length of the brush and extending a predetermined distance beyond 15 the inclined edges surrounding the opening, and longitudinal reinforcing members extending about the device and around the opening and integral with the pull-on tab.

4. A one-piece finger stall tooth brush made of 20 rubber-like material and having a base, an integral closure extending from said base having one end closed with a finger receiving opening opposite the closed end thereof, flexible rubber teeth extending from said base, the closure at the open 25 end thereof having its edges inclined upwardly and forwardly from said base to permit ready access of a finger in said opening, a pull-on tab integral with the closure at the upper side thereof and extending a predetermined distance beyond 30 the upper free edge of the closure at the open end thereof, said receiving opening being provided with a contracting rib portion for holding the tooth brush in position.

5. A one-piece finger stall gum manipulator 3 made of rubber-like material and having a base, an integral closure extending from said base having one end closed with a finger receiving opening opposite the closed end thereof, flexible rubber teeth extending from said base, the closure 4 at the open end thereof having its edges inclined upwardly and forwardly from said base to permit ready access of a finger in said opening, a pull-on tab integral with the closure at the upper side thereof and extending a predetermined distance beyond the upper free edge of the closure 5 at the open end thereof, longitudinal ribs extending about the brush, and an additional bead extending about the opening and the projecting end of said tab, said receiving opening 6 being provided with a rib to permit easy application and removal of the manipulator.

6. A one-piece finger stall tooth brush made of rubber-like material and having a base, an integral closure extending from said base having one end closed with a finger receiving opening opposite the closed end thereof, flexible rubber papillæ extending from said base, the closure at the open end thereof having its edges inclined upwardly and forwardly from said base to permit ready access of a finger in said opening, a pull-on tab integral with the closure at the upper side thereof and extending a predetermined distance beyond the upper free edge of the closure 7 at the open end thereof, said pull-on tab increasing in thickness from the closed end toward the open end.

RODERICK G. STEVENS.
